UNITED STATES PATENT OFFICE.

LEWIS F. RICHARDS, OF MILLVILLE, NEW JERSEY, ASSIGNOR TO T. C. WHEATON COMPANY, OF MILLVILLE, NEW JERSEY.

DESIGN FOR A BOTTLE.

SPECIFICATION forming part of Design No. 36,479, dated August 4, 1903.

Application filed April 4, 1903. Serial No. 151,195. Term of patent 7 years.

To all whom it may concern:

Be it known that I, LEWIS F. RICHARDS, a citizen of the United States of America, and a resident of Millville, county of Cumberland, 5 State of New Jersey, have invented a new, original, and ornamental Design for Bottles, of which the following is a description, reference being had therein to the accompanying drawings, in which—
10 Figure 1 is a side elevation of the front of the bottle; Fig. 2, a side elevation of the back of the bottle; and Fig. 3 a bottom view of the bottle.

Having thus shown my invention, what I claim, and desire to secure by Letters Patent, 15 is—

The ornamental design for a bottle as shown.

In testimony whereof I hereunto affix my signature, in the presence of two witnesses, 20 this 1st day of April, 1903.

LEWIS F. RICHARDS.
